INVENTOR

John Darby

UNITED STATES PATENT OFFICE.

JOHN DARBY, OF SUMMIT, NEW JERSEY.

POWDER-PUFF.

1,359,232.

Specification of Letters Patent. Patented Nov. 16, 1920.

Application filed January 17, 1920. Serial No. 352,102.

To all whom it may concern:

Be it known that I, JOHN DARBY, a citizen of the United States, a resident of Summit, in the county of Union and State of New Jersey, have invented certain new and useful Improvements in Powder-Puffs, of which the following is a specification.

This invention relates to powder puffs, and has for its objects the production of a powder puff consisting of a minimum number of parts, simple in construction and manufacture and yet strong and durable.

These and other objects and advantages will be set forth in part hereinafter and in part will be obvious herefrom, such objects and advantages being obtained by the means pointed out in the accompanying claims.

The invention consists in the novel parts, construction, arrangement and improvements herein shown and described. Of the drawings:

Figure 1 is a perspective view of the powder puff,

Fig. 2 is an enlarged transverse section,

Fig. 3 is an enlarged transverse section of the body or shell member,

Fig. 4 is a side elevation of the body member showing the returned and slotted flange,

Fig. 5 is an enlarged section of the returned flange of the body member showing a bent over corner, of one of the members of said returned flange and,

Fig. 6 is an enlarged plan view of the returned flange, showing the bent over corners of the castellated parts of said flange.

Referring to the drawings, 1 is the shell or body member, 2 is the pile cloth or face of the powder puff and 3 the handle or grip.

The body member 1 may be made of any suitable sheet metal and in general its form is that of a shallow pan with a downwardly flanged portion 4 and a returned or upwardly flanged portion 5, which is slotted as at 6, 6 to form upwardly extending fingers or tongues 7, 7 the corners of which are turned inwardly toward the flange 4 to form teeth 8, 8.

A portion of the top of body 1 is forced out as at 10 to form a hinge holding for the ring handle 3. Said ring may be split and made of spring wire with the split portion housed within the hinge 10.

The bottom or closed portion of body 1 may be either flat or crowned, or may be embossed in any suitable manner and its

outer or exposed surface may be plated or enameled to give a pleasing and artistic appearance.

The method of assembling the pile cloth 2 with the body member 1 is clearly shown in Fig. 2. The pile cloth is cut in disks of suitable diameter to allow the edges to be turned up to cover the outer or upwardly extending flange 5 and over the upper edges of tongues 7, 7 of said flange and downwardly into the channel or space 9 between flanges 4 and 5. While the cloth 2 is in this position, the tongues 7, 7 are pressed inwardly by any suitable means, forcing the pile cloth 2 against the flange 4, the teeth or points 8, 8 biting into the cloth hold it fast and prevent it from working loose from the body member 1.

It will be obvious from the structure disclosed, that a powder puff made in this manner will have a minimum number of parts, will be easy to assemble and consequently cheap to manufacture.

It will be understood from the foregoing that devices have been provided realizing the objects and advantages herein pointed out, together with other objects and advantages.

It will be further understood that many changes may be made from the precise form of such devices herein shown and described within the accompanying claims, without departing from the principles of the invention and without sacrificing its objects and advantages.

I claim:

1. A powder puff comprised of a single cupped body member provided with a returned flange and a piece of cloth stretched over the open cup side of said body member and held between said body member and said flange.

2. A powder puff comprising a single cupped body member having a handle attached thereto, a returned flange on said body member and a piece of cloth stretched over the open side of said body member and held between said flange and said body member.

3. A powder puff comprising a single cupped body member provided with a returned slotted flange and a piece of cloth stretched over the open cup side of said body member and held between said body member and said slotted flange.

4. A powder puff comprising a single cupped body member provided with a returned slotted and toothed flange and a piece of cloth stretched over the open cup side of said body member and held between said body member and said slotted and toothed flange.

In testimony whereof I have signed my name to this specification in the presence of two subscribing witnesses.

JOHN DARBY.
